UNITED STATES PATENT OFFICE.

HOWARD E. COFFIN, OF DETROIT, MICHIGAN, ASSIGNOR TO OLDS MOTOR WORKS, OF DETROIT, MICHIGAN, A CORPORATION OF MICHIGAN.

CARBURETER FOR HYDROCARBON-ENGINES.

No. 831,832.

Specification of Letters Patent.

Patented Sept. 25, 1906.

Application filed October 17, 1904. Serial No. 228,853.

To all whom it may concern:

Be it known that I, HOWARD E. COFFIN, a citizen of the United States, residing at Detroit, in the county of Wayne and State of Michigan, have invented certain new and useful Improvements in Carbureters for Hydrocarbon-Engines, of which the following is a specification, reference being had therein to the accompanying drawings.

10 The invention relates to carbureters for use in connection with explosion-engines, and more particularly designed to be used on motor-vehicles.

In the construction of carbureters for motor-vehicles it is customary to provide means for variably restricting or throttling the inlet from the carbureter to the cylinder of the engine, so as to regulate the force of explosion and the speed of the engine. It is also common with a certain type of carbureters to obtain a variation in the quantity of oil introduced into the mixing-chamber by the variable suction produced by the operation of the throttle. Thus under ordinary conditions, 25 where the vehicles run upon a level road, the opening of the throttle will cause an increased quantity of oil to be drawn into the mixing-chamber and absorbed by the large volume of air passing therethrough, while the 30 closing of the throttle will correspondingly diminish the quantity of oil and air.

The means of regulation above, while operating satisfactorily under ordinary conditions, have been found to be inadequate under other conditions—for example, when the vehicle is moving slowly under a large load—as where climbing a steep hill the maximum power of the engine is desired, and consequently the throttle is wide open. At the 40 same time on account of the slow movement of the piston the suction produced is not great and frequently results in a failure to introduce sufficient oil in the mixing-chamber to produce a proper explosive mixture. 45 Thus at a time where the greatest certainty of action is desirable there is the greatest likelihood of failure in explosion.

It is one of the objects of the present invention to obtain a construction in which a 50 sufficient quantity of oil will always be drawn into the mixing-chamber, even where the movement of the piston is slow.

To this end the invention consists in the

peculiar construction of the automatic regulating-valve for variably restricting the air-conduit adjacent to the oil-inlet nozzle according to the suction produced by the engine and independent of the regulation of the throttle.

The invention further consists in the peculiar construction, arrangement, and combination of parts, as hereinafter set forth.

In the drawings, Figure 1 is a vertical longitudinal section through the carbureter. Fig. 2 is a top plan view thereof, partly in section.

A is a suitable casing in which is an oil-chamber B, the oil therein being maintained at a constant height by a float C, which controls a valve D, governing an inlet from the oil-supply conduit E. Adjacent to the chamber B is a chamber F, in which is arranged the oil-discharge nozzle G, which receives the oil through a passage H, connecting with the chamber B. The nozzle G is arranged vertically and centrally of the chamber F and is in such relation to the float C in the chamber B that the level of the oil is maintained a slight distance below the upper end of the discharge-nozzle. At the upper end of the 80 nozzle is preferably provided a plurality of radial jet-passages a, through which the oil when discharged is directed into different portions of the chamber F.

The chamber F is provided at its base with 85 an air-inlet opening F' and near its upper end is provided with a lateral discharge-opening F². I is a flange for connecting the casing A with a conduit leading to the engine-cylinder.

The throttle-valve for controlling the amount of explosive mixture drawn from the carbureter is located adjacent to the discharge-opening F² and is preferably in the form of a hollow rotary valve J. This valve 95 is seated in a cylindrical portion A' of the casing A and is provided with a port b, adapted to be registered with the lateral discharge-opening F² in the casing. At the upper end of the hollow valve is an operating-stem K, 100 extending outward through an apertured cap L at the upper end of the casing A'. This cap is recessed to form a chamber in which is located a coil-spring M, said spring being connected to the valve J and adapted to rotate 105 the same into its normal position, where the

discharge-opening F^2 is almost closed. The opening of the valve is effected by a lever N , attached to the stem K and adapted to rotate the same against the tension of the spring M . Thus by means of suitable connections with the lever N the throttle may be adjusted to vary the area of the discharge-opening F^2 .

The construction as thus far described will be open to the objection which has been referred to—viz., that the quantity of oil drawn into the chamber F depends upon the suction of the air-current passing therethrough or, more accurately, to the velocity of the air-current passing immediately adjacent to the oil-discharge nozzle. As a consequence if the throttle is wide open while the piston of the engine is moving slowly the velocity of the air-current might not be sufficient to draw into the chamber F the required quantity of oil. To overcome this defect, I have provided an automatic regulator-valve of the following construction: O is a disk, preferably formed of thin sheet metal, provided with a facing of some light tough material, such as vulcanized fiber, this lining being indicated at c . The valve O is provided with a central aperture through which the nozzle G projects and an annular passage d being left between the nozzle and the inner edge of the valve. The valve is seated upon a suitable spider or apertured plate P , so as to be directly in the path of the air-current passing from the inlet-opening F' through the chamber F to the discharge-opening F^2 . The diameter of the valve O is preferably substantially the same as that of the cylindrical portion A' of the casing A , and said casing is preferably provided with an enlargement A^2 below the valve J and above the seat P for the valve O . This enlargement will provide a passage for the air around the edge of the disk when the latter is lifted from its seat, as will be hereinafter described. The valve O is yieldingly held to its seat by elastic pressure, preferably formed by a spring Q . As shown, this spring is of a conical form having its lower end resting upon the disk O near the margin thereof and its upper end engaging with a central bearing R . This bearing R is preferably formed on a threaded shank which passes axially through the stem or shank K for rocking the valve J . The upper end of the shank R is provided with a head e , with which a wrench or other adjusting instrument may be engaged, so that by rotating the shank R the tension of the spring Q may be varied.

With the construction described in operation the oil from the conduit E will pass into the chamber B and fill said chamber to a predetermined level, the float C then operating to close the valve D and prevent further admission of oil. A removable strainer S is preferably provided in this inlet-pipe, so as to prevent admission of foreign material into

the chamber B . From the chamber B the oil passes through the channel H into the nozzle G , which nozzle is preferably provided with a needle-valve T therein, by means of which the flow of oil therethrough may be regulated. The oil rises in the nozzle G to a level within the chamber B , which is slightly below the upper end of the nozzle. A suction being produced by the movement of the piston in the engine-cylinder, an air-current will be drawn through the chamber F , entering the aperture F' and passing through the annular space d adjacent to the nozzle G into the upper portion of the chamber F within the hollow valve J and thence through the aperture F^2 to the conduit leading to the engine-cylinder. On account of the restriction or diminished area of the annular passage d the velocity of the air-current is greatly increased at this point, and as a consequence a suction is created at the nozzle which will lift the oil and spray it from the jet-opening a into the air-current.

When the throttle-valve J is in the position of adjustment to nearly close the outlet-port F^2 , the operation will continue as just described—i.e., all of the air entering through the aperture F will be compelled to pass through the annular passage d adjacent to the nozzle G . As soon, however, as the throttle J is adjusted to produce a larger opening into the passage F^2 the pressure of air upon the lower face of the disk O will lift said disk, so as to permit the passage of air around the periphery of the disk and through the enlargement A^2 into the mixing-chamber. At the same time a portion of the current will pass through the annular passage d . The greater the opening of the port F^2 the greater will be the rise of the disk O , and as a consequence the restriction for the air-current caused by the disk valve O will be proportionate to the restriction by the throttle J , and at all times a portion of the air-current will pass immediately adjacent to the nozzle G through the annular passage d . The rise of the valve O will not, however, always be the same for the definite adjustment of the throttle-valve J , but will be determined to as large an extent by the speed of the piston as by the degree of throttling. Thus where the engine is running slowly the throttle may be widely opened and the valve-disk O will nevertheless remain comparatively close to its seat, so as to produce the requisite velocity of the air-current passing through the annular passage d to spray the oil from the nozzle G . The primary function of the valve O is thus to at all times produce a suction air-current adjacent to the nozzle, while it also instantaneously responds to any change in the adjustments of the throttle or in the speed of the engine, which creates a greater suction. It will be observed that this valve O is always subjected on one side to the pressure of

- the incoming air-current and on its opposite side to the pressure of the spring Q. As the pressure of the air-current is continually varying, it is evident that the valve will ordinarily be in constant fluctuation, and it is also evident that each time the direction of movement is changed the inertia must be overcome. It is therefore desirable that the factor of inertia should be reduced to the minimum, and this result I have produced by forming the valve O as a thin disk, the mass of which in relation to the area operated upon by the air is very slight. By such a construction the sensitiveness of the valve O is greatly increased, and, furthermore, the pound which would be caused by a relatively heavy valve in striking against its seat is prevented. The fiber lining for the valve is also effective in preventing wear by the striking of the valve against its seat. By means of the threaded stem R the tension of the spring Q may be adjusted so as to produce the proper degree of resistance to the movement of the disk O. The disk is guided in its movement by the conical shape of the spring Q, which always tends to center the disk, and peripheral guides f are also preferably provided adjacent to the enlargement A² of the casing. Stop-lugs h project from the valve J and limit the upward movement of the disk O. The shank of the nozzle G preferably extends outward through the wall of the casing, and the needle T may be adjusted at the end of said shank, with which it preferably has a screw-threaded engagement, as at g. When properly adjusted, the needle-valve is guarded from change by the cap U, having a threaded engagement with the end of the shank of the nozzle G.
40. What I claim as my invention is—
1. In a carbureter, the combination with a casing, through which an air-current is drawn, of an oil-inlet nozzle projecting therein, an annular-disk valve seated in said casing and contracting the air-passage around the discharge end of said nozzle, one face of said valve being exposed to the pressure of the air-current, tending to lift said valve from its seat, and means for yieldingly pressing said valve to its seat.
  2. In a carbureter, the combination with a casing through which the air-current is drawn, of an oil-inlet nozzle projecting into said casing, an annular-disk valve seated in said casing and contracting the air-passage surrounding the discharge end of said nozzle, one face of said valve being exposed to the pressure of the air-current, tending to lift the valve from its seat and the mass of said valve being small in relation to the area acted upon, so as to diminish the factor of inertia, and means for yieldingly pressing said valve toward its seat.
  3. In a carbureter, the combination with a casing, through which the air-current is drawn,
- of an oil-inlet nozzle extending axially within said casing, and an annular-disk valve surrounding the discharge end of said nozzle and seated in said casing, said valve being formed of a thin metallic plate with a non-metallic lining for contacting with said seat.
4. A carbureter, comprising a casing, through which the air-current is drawn, an oil-inlet nozzle projecting axially within said casing, an annular-disk valve surrounding the discharge end of said nozzle and marginally seated within said casing and a conical-helical spring, its large end bearing against said disk near the margin thereof, and its small end bearing against a central abutment within said casing, whereby said disk is yieldingly pressed toward its seat against the pressure of the air-current.
5. In a carbureter, the combination with a casing, through which the air-current is drawn, of a hollow rotary throttle-valve within said casing, controlling the discharge-opening in the side wall thereof, of an oil-inlet nozzle projecting into said casing, in axial alinement with said valve and directing the oil-discharge within the same, and an annular-disk valve surrounding the discharge end of said nozzle and marginally seated within said casing.
6. In a carbureter, the combination with a casing, through which the air-current is drawn, of a hollow rotary throttle-valve within said casing, controlling a discharge-port in the side wall thereof, an oil-inlet nozzle in axial alinement with said valve and directing the oil-discharge into the interior thereof, an annular-disk valve surrounding said nozzle and marginally seated with said casing, and a spring within said hollow valve yieldingly pressing said disk toward its seat against the pressure of the air-current.
7. A carbureter, comprising a casing, through which the air-current is drawn, a hollow rotary valve within said casing controlling a discharge-port in the side wall thereof, an oil-inlet nozzle extending into said casing and directed into said hollow valve, an annular-disk valve surrounding said nozzle and seated within said casing, and a conical helical spring within said hollow valve, having its large end bearing against said disk-valve and its small end against a central abutment.
8. In a carbureter, the combination with a casing, through which the air-current is drawn, of a hollow rotary valve controlling a discharge-port in the side wall of said casing, an oil-inlet nozzle directed into said hollow valve, a hollow cap for closing the end of said casing, through which said valve is entered, and a coil-spring within said hollow cap for yieldingly rotating said valve to its normal position.
9. In a carbureter, the combination with a casing, through which the air-current is drawn, a hollow rotary valve within said casing con-

trolling a discharge-port in the side wall thereof, the stem of said valve projecting outward from said casing, an oil-inlet nozzle extending into said casing in axial alinement 5 with said rotary valve, and adapted to discharge the oil within the same, an annular-disk valve surrounding said nozzle and seated within said casing, a conical helical spring within said hollow valve, bearing against said disk valve and an adjustable abutment for said spring, formed by a stem passing outward through the stem of said rotary valve.

10. In a carbureter, the combination with a casing, through which the air-current is drawn, of a hollow rotary valve within said casing, controlling a discharge-port in the side wall thereof, an oil-inlet nozzle projecting into said casing, directed into said hollow valve, an annular-disk valve surrounding 15 said nozzle, adjacent to the end of said hollow valve, a seat within said casing for said disk-valve, and an enlargement in said casing between said seat and hollow valve, whereby when said disk is lifted from its seat, an air-

passage is formed in said enlargement around 25 the periphery of the disk.

11. In a carbureter, the combination with a casing, having a cylindrical portion, a hollow rotary valve fitting within said cylindrical portion and controlling a discharge-port in 30 the side wall thereof, a valve-seat within said casing below said rotary valve, an annular-disk valve resting upon said seat and contracting the passage into said hollow valve, an oil-inlet valve projecting into the passage 35 contracted by said disk-valve, a spring for holding said disk valve to its seat, an enlargement within said casing between said seat and said hollow valve, and projections at the end of said hollow valve forming abutments for limiting the movement of said disk valve.

In testimony whereof I affix my signature in presence of two witnesses.
